UNITED STATES PATENT OFFICE.

JOHN W. COSGROVE, OF MEDFORD, MASSACHUSETTS, ASSIGNOR TO UNITED SHOE MACHINERY COMPANY, OF PATERSON, NEW JERSEY, A CORPORATION OF NEW JERSEY.

MACHINE FOR INSERTING FASTENINGS.

1,164,784.

Specification of Letters Patent. Patented Dec. 21, 1915.

Application filed February 18, 1914. Serial No. 819,440.

To all whom it may concern:

Be it known that I, JOHN W. COSGROVE, a citizen of the United States, residing at Medford, in the county of Middlesex and State of Massachusetts, have invented certain Improvements in Machines for Inserting Fastenings, of which the following description, in connection with the accompanying drawings, is a specification, like reference characters on the drawings indicating like parts in the several figures.

This invention relates to machines for inserting fastenings and particularly to machines for inserting fastenings to secure together the upper and the channel lip or rib or shoulder of the insole of a lasted shoe while the shoe is in lasted condition, a machine of the general type to which the invention particularly relates being shown in United States Letters Patent No. 1,059,984, granted April 29, 1913, to E. Erickson and J. W. Cosgrove.

An object of the invention is to improve machines for the purposes above outlined, and particularly machines of the type disclosed in said Letters Patent, to the end that the capacity of the machines may be increased and the quality of their work may be made more uniform.

In the machine disclosed in said Letters Patent the work to be operated upon is presented either to the staple guiding nozzle or to the staple clenching tool or anvil and the operator then depresses a treadle which first effects a relative movement of the staple guiding nose and the anvil to clamp between them the parts to be secured together by the staple, after which a further movement of the treadle actuates the mechanism for inserting and forming staples, the machine being so constructed that said mechanism performs a single operation and then automatically stops. Inasmuch as the machine is designed to insert the staples through the upper and insole channel lip or rib or shoulder at points located between the lasting tacks while the shoe is in lasted condition, it was assumed in designing this machine that to avoid the insertion of one staple on top of another, in case the operator did not remove his foot from the treadle quickly enough, it would be necessary to provide means for preventing the machine from repeating and in any event it would be necessary carefully to select the

point at which the staple should be inserted and carefully to press together the parts of the shoe through which the staple was to be driven. To this end the machine shown in said Letters Patent is provided with means for preventing more than one operation of the inserting mechanism for one clamping and actuating movement of the manually controlled means and the relative clamping movement of the staple guiding nose and the staple clenching anvil is effected manually. It is found in practice, however, that to require the operator to start the machine every time a staple is to be inserted reduces very materially the capacity of the operator and that, moreover, to require the machine to stop and to be started for each staple inserting operation causes very serious wear and tear of the machine and likewise reduces its possible capacity.

An important object of the invention is so to construct the machine that the clamping of the parts through which the staple is to be inserted may be effected automatically and that by a single actuation a plurality of staple inserting operations may be effected, the clamping mechanism being so constructed and operated that the operator may locate the shoe with sufficient accuracy for the purposes of the machine between the successive clamping and inserting operations.

A particular object of the invention is so to arrange the automatic clamping mechanism that the parts through which the staple is to be inserted may be automatically clamped above the line of insertion in a certain time relation to the additional clamping action exerted upon these parts below the line of insertion, provision being preferably made for varying this timing.

Other objects and important features of the invention will appear from the following description and claims when considered in connection with the accompanying drawings, in which,

Figure 1 is a perspective view of the upper part of a machine embodying the invention; Fig. 2 is a vertical section through the head of the machine, illustrating the operative connections by which the automatic movement of the staple clenching-anvil is effected; Fig. 3 is a detail view, showing portions of the connections between the

treadle and the clutch which are concealed in the other figures.

The principal operative parts of the machine are substantially identical with the corresponding parts of the machine shown in the Letters Patent No. 1,059,984, above referred to, the cams from which the various mechanisms are operated being connected to a main driving shaft 2 mounted in bearings 3 in the head 4 of the machine, said head being mounted upon a standard 8 which is carried upon a base, not herein shown, in which base is located a treadle, also not shown, through which the manual control 15 of the actuation of the machine is effected.

A driving pulley 10, loosely mounted upon the shaft 2, is arranged to be clutched to the shaft at the will of the operator by any suitable clutch mechanism, the clutch herein 20 illustrated being of the Horton clutch type. A clutch controlling arm 12 upon a rock-shaft 14 normally holds the clutch in its inoperative condition, the roller cage 16 of the clutch being provided with a stop portion 18 25 which normally engages a spring-cushioned dog 20 pivoted between ears 21 upon the end of the arm 12. When the shaft 14 is turned in a clockwise direction in Fig. 2, the dog 20 is lifted out of engagement with the stop 18 and the roller cage 16 is rotated by a spring, 30 not shown, in the usual manner to bring the usual rollers of the Horton clutch into clutching position between a clutch member fixed upon the shaft 2 and a cylindrical 35 surface upon the inside of the pulley 10. A spring 160 tends to maintain the arm 12 normally in its clutch releasing position. The brake arm 32 is also carried by the rock-shaft 14, surrounding an eccentric upon said 40 shaft and being moved into and out of engagement with the brake disk 30 by said eccentric as the rock-shaft is oscillated during the clutch releasing and clutch actuating movements of the lever 12.

45 The staple forming and inserting mechanism comprises, as in the machine of said Letters Patent above referred to, an outside former 34 arranged to slide in a guideway in the machine head, said outside former carrying at its forward end a tongue 42 which projects in front of the former and engages the work just before the staple is inserted to press together close to the line of insertion the parts through which the staple is to be 50 inserted. The outside former is provided upon its upper rear face with rack teeth 48 which mesh with teeth 50 of a segment rack carried by a lever 52 fulcrumed upon a rock-shaft 54 and having upon its other arm 55 56 a cam roll which enters a cam groove 57 in a cam disk 58 upon the main shaft 2. The outside former co-operates to form a staple with an inside former 60 carried upon a vertically movable plunger 62 having at its upper end a slotted head 64 through the slot in

which passes a bolt 66 carried by an arm 68 upon a rock-shaft 70. A spring 72 surrounding the hub of the arm and bearing against the upper side of the head 64 tends to keep the end of the head 64 in engagement 70 with the bolt 66 but permits lost motion after the inside former has come into its proper operative position, the staple formed about said inside former being driven by a driver 106 connected to the driver slide 118, 75 all as more fully described in said Letters Patent above referred to. The wire 84 from which the staple is to be formed is fed into position to be operated upon by the staple formers by feeding means comprising a 80 toothed feed wheel 86 against which the wire is pressed by a spring-pressed presser roll 88 geared to the feed wheel 86, said feed wheel being rotated through a pawl and ratchet mechanism, more fully described in 85 said Letters Patent, said pawl and ratchet mechanism being operated by a link 100 connected to the arm 76 of the means through which the inside former is operated.

90 The rock-shaft 14 which carries the clutch controlling arm 12 is provided with a second arm 154 from which depends a link 148, said link being provided with a hook 150 at its lower end and entering a slot in an arm 144 95 attached to the rock-shaft 164. The link 146 which extends to the treadle is connected at its upper end to the arm 144 and a pin 152 in the slot in said arm 144 is adapted to be engaged by the hook 150 when the link 146 100 pulls said arm 144 downward as the treadle is depressed. The rock-shaft 14 is thus rocked to throw the dog out of engagement with the stop 18 upon the roller cage 16 of the clutch. A spring 156 tends to keep the hook link 148 constantly in engagement with the pin 152.

105 It will be understood that all of the parts of the just described chain of connections are not necessary to the operation of the machine of this invention, several of these parts being retained in the illustrated construction for convenience in adapting the machine for operation in the manner of the machine described in the Letters Patent 110 above referred to in the event that such operation of the machine is desired. The machine herein shown, like the machine of said Letters Patent, is timed to insert a staple during the first part of the cycle of operations and then to form a staple and to stop with the staple formed. In order that the staple clenching anvil 123 may be brought into work clamping relation to the staple 115 guiding nose 122 in time to clamp together the parts through which the staple is to be driven, this anvil is shown as operated by connections to the mechanism which operates the outside former and the tongue 42 120 whereby the tongue 42 engages one side of 130

the parts through which the staple is to be inserted in a certain time relation to the engagement of the other side of said parts by the anvil 123. The anvil 123, as in the machine shown in said Letters Patent, is carried by a slide 124 which slides in a guide-way in a forward extension of the machine frame, the slide 124 being provided at its rear end with an upright portion 136 through which extends a bolt 134 having a forked extension 132 embracing a lever arm 162 upon the rock-shaft 164, said arm being connected at its end remote from said shaft to an extension 166 of the lever arm 56 by means of a link 168 forked at each of its ends and made in two parts having a threaded connection whereby the length of the link may be varied, said parts being locked in their different adjusted relations by a set 20 nut 170.

The length adjustment just described provides for varying the normal separation of the clenching tool or anvil 123 and the nose 122. To provide for an adjustment of the amount of clamping movement imparted to the clenching tool 123, the extension 166 of the lever 56 is provided with a series of holes 172 at different distances from the rock-shaft 54 whereby the pivot pin 174 by 30 which the link 168 is connected to the extension 166 may be located at different distances from said rock-shaft. To provide a yielding clamping action, a spring 138 surrounds the bolt 134 and is confined between 35 the upright 136 and a nut and washer upon the threaded end of said bolt. In order to provide both the requisite tension and the requisite compressibility, the spring 138 is made in two parts, as shown, one being 40 within the other.

The operation of the machine will be apparent from the foregoing description. It will be seen that when the operator depresses the treadle to start the machine after the lasted shoe has been presented to the anvil 123 or to the nose 122 in proper position to receive the first staple, the anvil will be automatically brought into work clamping relation to the nose and so long as the operator keeps his foot upon the treadle the anvil will be moved into and out of work clamping relation to the nose, being moved into work clamping relation just before the staple is inserted and out of work clamping relation just after the staple is inserted. By connecting the anvil up to the outside former this movement into and out of work clamping relation requires only a small part of the time consumed in the cycle of operations of the machine, since the machine stops with the staple formed, and, therefore, the operator has time enough to move the shoe into the proper position to receive the next staple before the anvil is again brought into work clamping position. Even if, by

chance, the operator should have located the shoe so that the staple is driven against one of the lasting tacks, no harm will be done owing to the yielding connection between the anvil and the outside former and owing to the fineness of the wire from which the staple is formed, the staple being merely crumpled up by its impact with the tack and dropping out of the way. It is found in practice, however, that the operator rarely fails to locate the shoe in proper position so that the staple will be driven through the parts to be united and clenched upon the anvil.

Having described my invention, what I claim as new and desire to secure by Letters Patent of the United States is:—

1. In a machine for attaching an upper to the channel lip or rib or shoulder of a sole by means of a staple, staple inserting means, means for automatically clamping together the parts through which the staple is to be inserted, and means connected to said last mentioned means to operate in a definite time relation thereto for bringing additional clamping pressure to bear upon the work below the line of insertion before the inserting operation.

2. In a machine for attaching an upper to the channel lip or rib or shoulder of a sole by means of a staple, staple inserting means, comprising a staple guiding nose against which the parts to be united are pressed, a staple clenching anvil movable toward and away from said nose, means for automatically bringing said anvil into work clamping relation to said nose, means acting in opposition to said anvil to bring clamping pressure to bear upon the work just below the line of insertion, and yielding connections between said anvil and said last mentioned means.

3. In a machine for attaching an upper to the channel lip or rib or shoulder of a sole by means of staples, staple inserting means, a staple guiding nose, a staple clenching anvil normally in inoperative position with relation to said staple guiding nose, and means for automatically moving said anvil into work clamping relation to said nose before the staple inserting operation, said means being adjustable to vary the extent of the clamping movement.

4. In a machine for attaching an upper to the channel lip or rib or shoulder of a sole by means of staples, staple forming and inserting means, a staple guiding nose, a staple clenching anvil, and means connected to said forming and inserting mechanism for automatically moving said anvil into work clamping relation to said nose before the staple inserting operation, said means being adjustable to vary both the normal opening between said anvil and said nose and the extent of the clamping movement.

5. In a machine for attaching an upper to the channel lip or rib or shoulder of a sole by means of staples, staple inserting means comprising a staple guiding nose 5 against which the parts to be united are pressed, a staple clenching anvil movable toward and away from said nose, means for automatically bringing said anvil into work clamping relation to said nose, means acting 10 in opposition to said anvil to bring clamping pressure upon the work just below the line of insertion, and connections between said last mentioned means and said anvil operating means whereby said two means 15 operate in a definite time relation to each other, said connections being adjustable to vary the extent of the relative movement with respect to each other of said anvil and of said means which acts in opposition to 20 said anvil.

6. In a machine for attaching an upper to the channel lip or rib or shoulder of a sole by means of staples, staple inserting mechanism, staple forming mechanism 25 comprising an outside former adapted to act as a guide for the staple during the staple inserting operation, said parts being constructed and arranged to operate in such time relation that the machine stops with 30 the outside former in staple forming position but not completely in staple guiding position, a staple clenching tool arranged to be brought into work clamping relation to the staple inserting mechanism, means 35 for operating said outside former, and con-

nnections between said clenching tool and said former operating means arranged to move said clenching tool automatically into work clamping position during the completion of the movement of said former into 40 staple guiding position.

7. In a machine of the class described, staple inserting means, staple forming means comprising an outside former constructed to serve also as a guide for the 45 staple during the inserting operation, means for operating said parts in such time relation that the machine stops with the staple formed but with the outside former not completely in its staple guiding position, a 50 clenching tool arranged to be brought into work clamping relation to said inserting means, and connections between said clenching tool and said outside former operating means whereby said clenching tool is automatically brought into work clamping position during the completion of the movement of said outside former into 55 staple guiding position and is moved out of work clamping position during the first part of 60 the movement of the outside former out of staple guiding position.

In testimony whereof I have signed my name to this specification in the presence of two subscribing witnesses.

JOHN W. COSGROVE.
